UNITED STATES PATENT OFFICE

2,464,762

PULSER TUBE

Robert C. Hilliard, Salem, Mass., assignor to
 Sylvania Electric Products Inc., Salem, Mass.,
 a corporation of Massachusetts

Application September 15, 1945, Serial No. 616,601

8 Claims. (Cl. 176—122)

1

This invention relates to gaseous discharge tubes and particularly to those of the type in which the source of electrons is a cathode spot. It may be designed, if desired, so that the dissipation of heat at the electrode makes the tube useful in giving rapid capacitor discharges. It may be used as a strobotron and for other purposes, as in combustion engine ignition circuits.

An object of this invention is to provide a cold-cathode, gaseous discharge tube which will be a source of extremely rapid and distinct flashes or pulses.

Another object is to provide an electron discharge tube which functions at very high voltages.

Another object is to provide a low pressure discharge tube small in size and capable of handling high average currents.

A further object is to provide a rigid discharge tube which will give rapid and distinct pulses of current when used in connection with a vibrating unit, a motor, or the like.

A feature of this invention is the use of a ceramic cup to enclose and insulate the anode and grid. Another feature is the use of vent holes in one end of said ceramic cup to allow the cathode to dissipate heat with the sputtered material to the walls of the tube, thereby cooling sufficiently to be useful in high voltage circuits. Another feature is the rigid mounting of the electrodes to permit the device to withstand use in a motor or any vibrating unit.

Other objects and features of this invention will be explained hereinafter, and will be particularly pointed out in the claims.

Figure 1 is a perspective view of the cold-cathode gaseous discharge tube.

Figure 2 is a longitudinal sectional view of said cold-cathode, gaseous discharge tube enlarged.

In Figure 1, the anode wire 1 of tantalum is welded to material suitable for sealing to glass and is sealed into the glass sleeve 2 which supports the carbon grid 3. The cylindrical carbon grid 3 and the anode 1 are enclosed in an insulating ceramic cup 4 designed with vent holes 5 at the cathode end.

The gas, expanding because of the discharge, can blow out through the holes 5, together with some of the sputtered caesium. This releases the pressure inside the ceramic cup and may reduce

the amount of sputtered material therein also. It may also help to dissipate the heat, but the latter effect may also be achieved by adding cooling fins to the outside of the cathode cup, if desired.

The open cathode cup 6, with its internal filling 10 of low work function material allows intimate contact with the gas without formation of a glow on the outside. The lead-in wire 7, and 10 the support wire 9 are positioned to support and to make compact and rigid the assembled parts of the tube. The glass envelope 8 may be filled with helium at low pressure to further quicken the response of the device and to increase the 15 "hold-off" factor.

In Figure 2, the tantalum anode is sealed into the glass sleeve and surrounded by a cylindrical carbon grid; both anode and grid are insulated and enclosed by a ceramic cup. The wires 7 and 9, 20 one of which, 7, is a lead-in wire, support the cup and pass to the cathode which is covered with caesium chloride and aluminum, material which on sputtering does not readily cling to other parts of the tube. Caesium goes off as a gas through 25 the vent holes in the ceramic cup and dissipates the heat.

What I claim is:

1. A gaseous discharge tube comprising a container, a gaseous filling therein, an anode therein, 30 a cylindrical carbon electrode around said anode, a cathode having material of low work function on its inner surface, an insulating cylinder extending from said cathode and enclosing said carbon electrode, and lead-in means to said cathode, said anode, and said carbon electrode.

2. The combination of claim 1, in which the insulating cylinder has holes therein between the cathode and carbon electrode for the diffusing of gas.

3. The combination of claim 1, in which the anode is a tantalum wire.

4. A gaseous discharge tube comprising a sealed container, a filling of gas at low pressure therein, a metal cup cathode, a filling of low work function material therein, a hollow insulating cylinder fitting into said cathode cup and extending therefrom, a hollow cylindrical carbon electrode inside said cylinder and spaced from said cup, a wire anode inside said carbon electrode 45 but spaced therefrom, a lead-in wire connected to

tending out of said glass sleeve, and a lead-in wire contacting said carbon cylinder and extending through the stem press.

4. The combination of claim 5, in which the gas filling is helium.

5. The combination of claim 1, in which the gas filling is helium.

6. The combination of claim 4, in which the gas filling is helium.

ROBERT C. HILLIARD.
